UNITED STATES PATENT OFFICE.

THOMAS JAMES ROUSSEL, OF HAMILTON, ONTARIO, CANADA.

WINDOW.

1,110,717.

Specification of Letters Patent. Patented Sept. 15, 1914.

Application filed December 22, 1913. Serial No. 808,191.

To all whom it may concern:

Be it known that I, THOMAS JAMES ROUSSEL, of the city of Hamilton, in the county of Wentworth, in the Province of Ontario, 5 Dominion of Canada, builder, have invented certain new and useful Improvements in Windows, of which the following is the specification.

My invention relates to improvements in 10 windows and more particularly to the kind in which the sashes are capable of being revolved, and the object of the present invention is to devise a weatherstrip adapted to be applied to the sides of the sash which will 15 keep out the draft and which will at the same time be capable of being thrown back to permit of the sash being revolved.

A further object is to devise means for 20 limiting and adjusting the lateral movement of the weatherstrips to allow for shrinkage or swelling of the sash.

A further object is to devise a weatherstrip for the above purpose which will more effectually keep out the draft than is the 25 case with the present form of weatherstrips for revolving sash windows at present in use, and a still further object is to construct a weatherstrip which can be more readily and cheaply applied than is at present the case.

30 In general the structure comprises a window having vertical grooves in the side edges of the sash and the inner face of the sash being rabbeted at the side edges thereof, sliding bars adapted to be connected to the sash cords, the sash being swingably mounted on said sliding bars, weatherstrip bars each comprising two parallel bars of substantially equal width suitably connected together, adjustable brackets having inwardly extending fork-shaped ends, pins on the inner faces of the inwardly turned ends, plates adapted to be secured to the sides of the frame of the window, leaf springs interposed between the plates and the brackets, 45 screws extending through the brackets and plates and threaded into the latter, and links pivotally connected between the parallel bars of the weatherstrip intermediately of the length of the same, said links having slots 50 in their free ends, and said pins on the inwardly turned ends of the brackets adapted to slide in said slots, all as hereinafter more particularly described and illustrated in the accompanying drawing, in which:—

55 Figure 1 represents an elevation of a

window constructed according to my invention. Fig. 2 is a vertical cross-section thereof. Fig. 3 is a horizontal section thereof taken through the lines *b*—*b'* (Fig. 1). Fig. 4 is a horizontal section through the lines *a*—*a'* (Fig. 1). Fig. 5 is an enlarged perspective detail of one of the sets of parallel weatherstrip bars. Fig. 6 is a side view thereof. Fig. 7 is a perspective detail of the adjustable plate, bracket and spring. 65 Fig. 8 is a plan view of one of the links. Fig. 9 is a horizontal section of a modified form. Fig. 10 is a horizontal section of the modified form showing the manner in which the bracket is connected to the link and 70 Fig. 11 is a vertical cross-section of the modified form showing the pulley stiles of the window frame.

Like characters of reference indicate corresponding parts in the different views. 75

1 is the frame of the window. 2, 2 are the sashes of the window. 3, 3 are the sliding bars to which the sashes are swingably connected. 4, 4 are the grooves in the side of the sash and 5, 5 are the rabbets. 6, 6 are 80 parting strips between the sashes. 7, 7 are the parting strips on the inside of the window. 8, 8 and 8', 8' are the bars of the weatherstrip suitably spaced apart and rigidly connected together by the rivets 9, 9, 85 it being understood that the said bars 8 and 8' are respectively parallel to each other and are of equal width. 10, 10 are vertical strips secured to the frame of the window behind the weatherstrip bars. 11 is a plate adapted 90 to be secured in the sides of the frame. 12 is an adjustable bracket having an inwardly turned end 13 with a forked extremity 14. 15 is a pin on the inner face of the inwardly extending portion. 16 is a leaf spring interposed between the plate 11 and the bracket 12. 17 is a screw extending through the bracket and threaded through the plate 11. 18 is a link having a hole 19 therethrough, 100 said link being pivotally connected between the parallel bars 8 and 8' by one of the rivets 9 extending through the hole 19 therein. 20 is a slot in the link 18.

In the modification shown in Figs. 9 to 11 inclusive, the sides of the frame have vertical grooves 21 therein into which a modified form of sliding bar 3' is inserted. The sashes 2 are swingably connected to the said sliding bars and the pulley cords 22 are suitably connected to the sliding bars. In this 110

modification additional grooves 23 are cut in the sides of the frame and the parallel bars 8 and 8' are adapted to be thrown back into the same in order that the sash may be revolved. In this construction the parting strips are done away with and the sliding bars being of much smaller size are preferably constructed of suitable metal.

The device is operated as follows:—To weatherstrip the window the bars 8 and 8' are pushed into the grooves 4 and the rabbits 5 respectively, the same being finally pushed slightly outward to lock the forked end 14 of the bracket around the center rivet 9 to prevent displacement of the bars. When in this position the sashes can be raised or lowered at will without interfering with the bars, but when it is desired to swing either of the sashes for ventilating or cleaning purposes the weatherstrip bars are thrown back against the frame when it will be seen they will be clear of the sashes 2 and will permit of the latter being swung into the desired position.

Further should it be desired to adjust the bars the screws 17 can be turned and thus the adjustable bracket 12 moved laterally which will limit the lateral movement of the bars. This is very desirable as it is found that sashes invariably swell and consequently bars that have no means of being adjusted laterally to limit their movement would otherwise stick in the grooves and rabbits in the sash. Frequently also the sashes shrink and consequently by moving the adjustable bracket relative to the plate an adjustment can be made in this case also. The leaf springs 16 are adapted to hold the adjustable brackets in the correct position.

In the modification shown in Figs. 9 to 11 inclusive, as above stated the parting strips have been done away with, but with the exception of this the construction is the same as in Figs. 1 to 4 inclusive. Hitherto windows have been constructed with sliding bars in which one bar is wider than the other, in fact the front bar is adapted to butt up against the edge of the sash. It is found that the air gets through this butt joint whereas it is impossible in the present form where both bars are of equal width, one fitting into a groove in the side of the sash and the other in a rabbet in the face thereof, for air to get through as it has to travel a much more circuitous path than is otherwise the case; also the adjustable bracket is of great advantage as has been stated above.

Many modifications may be made in the invention without departing from the spirit of the same or the scope of the claims and the form shown is to be taken in an illustrative and not in a limiting sense. For instance although I have described my device as chiefly applied to the construction shown in Figs. 1 to 4 inclusive, it is to be understood

that it can with equal facility be applied to the construction shown in Figs. 9 to 11.

What I claim as my invention and desire to secure by Letters Patent is:—

1. In a revolving sash window the combination with the sash and frame, of weatherstrips, each comprising suitably spaced parallel bars, laterally adjustable brackets secured to the sides of the frame, each having an inwardly turned end, a pin on the inner face of each inwardly turned end, and links pivotally connected between the bars of the weatherstrip intermediately of the length of the same and pivotally connected to the inwardly turned end of the corresponding bracket. 70

2. In a revolving sash window the combination with the sash and frame, of weatherstrips, each comprising suitably spaced parallel bars, laterally adjustable brackets secured to the sides of the frame, each having an inwardly turned end, a pin on the inner face of each inwardly turned end, links pivotally mounted between the bars of each weatherstrip intermediately of the length of the same and having a longitudinal slot in each, said pin inserted into said slot of the corresponding link. 85

3. In a revolving sash window the combination with the sash and frame, of weatherstrips, each comprising suitably spaced parallel bars, plates secured in the sides of the frame, brackets, each having an inwardly turned end, and a pin secured on the inner face of each inwardly turned end, a leaf spring interposed between each bracket and the corresponding plate, a screw extending through each bracket, leaf spring, and threaded through the corresponding plate, links pivotally connected between the bars of each weatherstrip intermediately of the length of the same, said links having longitudinal slots therein, and said pins inserted into said slots. 95

4. In a revolving sash window the combination with the sash and frame, of weatherstrips, plates secured in the sides of the frame, brackets, each having an inwardly turned end, and a pin secured on the inner face of each end, a leaf spring interposed between each bracket and the corresponding plate, a screw extending through each bracket, leaf spring, and threaded through the corresponding plate, links pivotally connected to each weatherstrip intermediately of the length of the same, said links having longitudinal slots therein, and said pins inserted into said slots. 110

5. In a revolving sash window the combination with the sash, and a frame, of weatherstrips, brackets secured to the sides of the frame, each having an inwardly turned end, a pin on the inner face of each end, links pivotally mounted on each weatherstrip intermediately of the length of the same, each 125

of said links having a longitudinal slot therein, and said pins inserted into said slots.

6. In a revolving sash window the combination with the sash, and a frame, of weatherstrips, laterally adjustable brackets secured to the sides of the frame, each having an inwardly turned end, a pin on the inner face of each end, links pivotally mounted on each weatherstrip intermediately of the length of the same, each of said links having a longitudinal slot therein, and said pins inserted into said slots.

7. In a revolving sash window the combination with the sash, and a frame, of weatherstrips, plates secured in the sides of the frame, brackets, each having an inwardly turned end, and a pin secured on the inner face of each end, a leaf spring interposed between each bracket and the corresponding plate, a screw extending through each bracket, leaf spring, and threaded through the corresponding plate, links pivotally mounted on each weatherstrip intermediately of the length of the same, said links

having longitudinal slots therein and said pins inserted into said slots.

8. In a revolving sash window the combination with the sash, the frame, and sliding bars, the sashes being swingably mounted on the sliding bars, of weatherstrips, plates secured in the sides of the frame, brackets, each having an inwardly turned end, and a pin secured on the inner face of each end, a leaf spring interposed between each bracket 30 and the corresponding plate, a screw extending through each bracket, leaf spring, and threaded through the corresponding plate, links, pivotally mounted on each weatherstrip intermediately of the length of the 40 same, said links havng longitudinal slots therein and said pins inserted into said slots.

In testimony whereof I have signed at the city of Hamilton, in the county of Wentworth, in the Province of Ontario, Canada, 45 this 11th day of November 1913.

THOMAS JAMES ROUSSEL.
